UNITED STATES PATENT OFFICE.

NIELS PETER SAMUELSEN AND SØREN RASMUSSEN DEJGAARD, OF AALBORG,
DENMARK.

TABLE.

1,099,620.

Specification of Letters Patent.

Patented June 9, 1914.

Application filed April 8, 1913. Serial No. 760,088.

To all whom it may concern:

Be it known that we, NIELS PETER SAMUELSEN and SØREN RASMUSSEN DEJGAARD, manufacturers, subjects of the Kingdom of Denmark, residing at Nørregade 5, Aalborg, in Denmark, have invented certain new and useful Improvements in Tables; and we do hereby declare the following to be a full, clear, and exact description of the invention, 10 such as will enable others skilled in the art to which it appertains to make and use the same.

The present invention relates to tables with one or more extension plates placed 15 either at the ends—as a kind of drawer—or in the middle of the table, whose top then is divided straight through. Said extension plates are so mounted, that it suffices to draw out the end-pieces of the table-frame until the extension plate is lying 20 freely, after which said plate influenced by one or more springs will raise itself flush with the table-top and the outer parts of the plate then may be swung out to each 25 side.

An embodiment of the invention used in a table with extension plates at the ends is represented in the drawing.

Figure 1 shows a plan of the table-top 30 with one extension plate totally and the other extension plate partly drawn out, Fig. 2 is a vertical longitudinal section of the table and Fig. 3 is a transverse section of an extension plate totally drawn out.

The end-pieces *c* of the table-frame form 35 each the front-piece of a kind of drawer, in which an extension plate, consisting of a central part *a* and two side-pieces *b* hinged thereto, is so mounted that it is influenced 40 by one or more springs *b* tending to press it upward. The end-piece *c* is connected to two slide bars *d*, one at each side, in which one or more vertical grooves *h* are arranged, each groove *h* having at its top a horizontal 45 lengthening groove *i*. In the grooves *h* stop-lists *g* secured to the central plate *a* are mounted, said stop-lists acting also as guide-blocks for the plate *a* during its up and down movement.

When the end-piece *c* is drawn out, until 50 the extension plate is clear of the table-top *l*, the central plate *a* with its side-pieces *b* folded over it is pressed upward influenced by the springs *b*, until the stop-lists *g* strike 55 the inner end of the grooves *h*, and the up-

per surface of the central plate *a* then will be lying flush with the upper surface of the table-top *l*. The side-pieces *b* now are swung out each at its own side over the corresponding slide bar *d* and the end-piece *c* 60 is pressed so much in against the table-top *l*, that the inner edge of the extension plate is bearing against the outer edge of the table-top. In so doing the supports *e* of the side-pieces *b* will enter into the corresponding holes *f*, Fig. 3, under the table-top, and the stop-lists *g* will be pressed into the horizontal grooves *i*, so that they support the part 65 of the side-pieces *b* facing the central plate *a*. 70

If the extension plate is to be forced back under the table-top the end-piece *c* is drawn a little outward, until the supports *e* are withdrawn from the holes *f*. The side-pieces *b* are folded over the central plate *a* 75 and the extension plate as a whole is pressed a little against the table-top to bring the stop-lists *g* out of the grooves *i*. The extension plate now is pressed downward and simultaneously the end-piece *c* is pressed in 80 against the table-top *l*, so that the extension plate is brought under the said table-top, whereafter the end-piece *c* is brought to its place under the table-top.

The grooves *h* may at the bottom be provided with a corresponding horizontal lengthening as at their upper end, so that the stop-lists *g* may be brought into said lengthening grooves thereby securing the extension plate in its lower position. 85

If the extension plate is to be used as a leaf in a common double slide-bar extension table it is mounted in a corresponding manner but so that it is not moved when the table is expanded, and the stop-lists *g* catch 90 under the lower surface of the table top, when the leaf is raising, thereby stopping the said leaf in elevated position.

Claims:

1. An extension table, comprising in combination with a top, slide bars operative below said top and having vertical slide grooves in their opposing faces, a central top section vertically slidable between said slide bars, stop and guide lists on said central top section slidable in said vertical grooves, side pieces hinged on each side of said central top section, and springs below said central top section normally pressing the latter upwardly, said side bars also hav- 100
- 105
- 110

ing longitudinal extension grooves at the upper and lower ends of said vertical slide grooves to receive said stop lists for locking said central top section in elevated and folded position.

2. An extension table, comprising in combination with a top, slide bars operative below said top and having vertical slide grooves in their opposing faces, a transverse end piece connecting the free ends of said slide bars, central top section vertically slideable between said slide bars and inside of said end piece, stop and guide lists on said central top section slideable in said vertical grooves, side pieces hinged on each side of said central top section, and springs below

said central top section normally pressing the latter upwardly, said side bars also having longitudinal extension grooves at the upper and lower ends of said vertical slide 20 grooves to receive said stop lists when said central top section is brought into elevated position and said end piece is slid into position to support said central top section.

In testimony whereof, we affix our signatures, in presence of two witnesses.

NIELS PETER SAMUELSEN.
SØREN RASMUSSEN DEJGAARD.
